OPEN FIRE COOKER

Melvin H. Best, Pasadena, Calif., assignor to The Cal-Dak Company, San Marino, Calif., a corporation of California

Application January 4, 1956, Serial No. 39,591

Term of patent 3½ years

(Cl. D81—10)

FIG. 1.

FIG. 2.

FIG. 3.

Fig. 1 is a perspective view of an open fire cooker showing my new design;

Fig. 2 is a front elevational view of the cooker; and

Fig. 3 is a side elevational view of the side opposite that shown in Fig. 1.

I claim:

The ornamental design for an open fire cooker, as shown.
